UNITED STATES PATENT OFFICE

DARIUS E. SHRAUGER, OF ATLANTIC, IOWA

FRICTION SUPPORTING MEANS FOR SCREENS AND STORM SASHES

Application filed February 24, 1930. Serial No. 430,576.

This invention relates to that type of auxiliary closure members such as screens and storm sash designed to be formed in two units and to be employed in a double sash window frame in association with vertically arranged supporting bars carried by the side members of the window frame in such manner that the auxiliary closure members may be removed and replaced from within a building.

The particular object of this invention is to provide a friction holding means associated with the supporting bars for engaging one of the units of the auxiliary closure means for holding it in position while the other unit is being removed and replaced, and also for affording a close engagement of the closure unit with the supporting bars.

Another object of the invention is to provide an improved resilient means for frictionally engaging the side members of the closure unit, such as a screen or storm sash frame, for yieldingly holding the unit in the desired position and at the same time causing an intimate contact of the unit with permanently mounted supporting members.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a vertical sectional view of a window frame equipped with my improved friction holding devices which are here shown in engagement with the upper unit of a storm sash.

Figure 2 is a transverse vertical section of the same on the line 2-2 of Figure 1.

Figure 3 is a detailed horizontal view on the line 3-3 of Figure 1; and

Figure 4 is a perspective view showing a portion of one of the supporting bars with the improved friction holding means applied thereto.

The subject matter of the present application was shown and described in part in my

companion application filed September 24th, 1928, Serial Number 307,841.

In the accompanying drawings I have used the numeral 10 to designate the sill of an ordinary double sash window frame, which frame also includes side casing members 12, a head casing 14, side blind stops 16 and a head blind stop 18.

Within the window frame thus formed are designed to be mounted auxiliary closure members such as screens or storm sash which are formed in two units designated by the characters A and B.

To assist in mounting the units A and B I employ a pair of supporting bars C, one of which is mounted in vertical position on each of the side casings 12 and extending from the sill 10 to the head casing 14. Each of the supporting bars C is composed of a body portion 20 formed with an attaching flange 22 which is adapted to be secured to a side casing 12 immediately outside of a side blind stop 16. The body portion 20 of each supporting bar extends inwardly toward the median line of the window frame past the plane of the innermost margin of the blind stop 16 and terminates in a channeled track portion 24 which faces inwardly toward the interior of the building.

Each of the closure units A and B includes a side frame member or stile 26 which is formed at its outer margin with a laterally directed flange 28 adapted to be received within a channeled track portion 24 of one of the supporting bars.

My improved friction supporting means forming the subject matter of the present application is particularly designed for engaging the stiles 26 of the upper unit A for holding said unit in close engagement with the upper parts of the respective supporting bars C and with the flanges 28 engaging within the track portions 24.

The friction holding means is composed primarily of a plate 30 formed of sheet metal and having at one margin a laterally directed attaching flange 32 which overlaps the attaching flange 22 of one of the supporting bars C. The attaching flange 32 is rigidly secured to the attaching flange 22 by any

suitable means, such as spot welding at the points 33, or by rivets 34 or by a combination of both means. The plate 30 is of sufficient width to overlap and extend somewhat past the free margin of the supporting bar C to which it is attached, or in other words to extend inwardly toward the median line of the window frame beyond the innermost margin of the channel track 24 of the bar, and is so arranged that normally it engages the innermost flange of the track portion as shown in Figure 4.

The friction supporting plates 30 preferably are of somewhat less length than the vertical dimension of the upper closure unit A and extend substantially from the head casing 14 to a position somewhat above the position which is normally occupied by the lower margin of the unit A when in position.

The free margin of the friction plate 30 preferably is formed with a longitudinal rib or bead 36 for the purpose of lending strength and rigidity, and at its lower inner corner the plate is bent and shaped to form a lip 38 which is directed toward the interior of the building.

The closure units A and B may be removed and replaced by opening the lower sash of the window. The upper unit A is first placed in position by causing its stiles 26 to engage the lower parts of the supporting bars C and then sliding the unit upwardly with the flanges 28 in the channel portions 24, until the stiles 26 engage and pass between the friction plates 30 and the supporting bars. The passage of the stiles 26 behind the friction plates 30 is facilitated by the rearwardly turned lips 38 and the friction plates yield sufficiently to permit the stiles to pass into the proper position as clearly shown in Figure 3.

The unit A is moved upwardly until the upper margin engages the head casing 14 and its upper marginal portion preferably passes behind a transversely arranged strip 40 carried by said head casing in a position spaced inwardly somewhat from the upper ends of the supporting bars C.

The tension exerted by the friction holding plates 30 is sufficient to hold the upper unit A in place until such time as the lower unit is mounted beneath it and such tension also serves to produce a tight fit of the unit A against the supporting bars and to prevent vibration and rattling.

If desired, the inherent resilience of the friction plates 30 may be supplemented by backing springs 42 which are coiled on studs 44 carried by the plate 30 and project loosely through bracket members 46 spaced inwardly from the plates. The brackets 46 may be formed at their ends with attaching flanges or ears 48 overlying the flanges 32

of the friction plates and held in place by the rivets 34.

After the upper unit A has been placed in position the lower unit B may be placed against the lower portions of the supporting bars C and held by suitable means, such as pivoted latches 50 carried by the supporting bars. The lower margin of the unit B may be caused to engage behind stops 52 located adjacent the sill 10 and the upper marginal portion of the unit B may be provided with a flange 54 overlapping the lower rail of the unit A, thus producing a tight joint between the two units.

The resiliently mounted friction holding plates 30 provide economical, convenient and efficient means for automatically gripping and securely holding the upper unit A in such manner that said unit may be easily and quickly removed and replaced by a simple vertical sliding movement relative to the supporting bars C.

The principal parts of this structure, including the frames of the auxiliary closure units, whether screens or storm sash, and also including the supporting bars and the friction holding plates may be made of sheet metal by stamping and thus a cheap, durable structure is provided. Furthermore the parts are not bulky and are thus easily handled and stored and they present a pleasing appearance when mounted on a building.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. Friction supporting means for a window closure unit, comprising a rigidly mounted supporting member, a friction plate arranged parallel therewith, a bracket substantially parallel with and spaced from the plate, a stud carried by the plate and extending loosely through the bracket, and a tension spring coiled on said stud for causing the plate to exert yielding pressure on a unit mounted between itself and the supporting member.

2. Friction supporting means for a window closure unit, comprising a supporting bar formed with a marginal attaching flange, a friction plate arranged parallel with the supporting bar and formed with a marginal flange contacting the attaching flange thereof, means for conjointly securing said flanges to a window side casing member, brackets secured to the casing member and having parts spaced from said friction plate, and springs mounted between said parts and the friction plate for urging the latter toward

said supporting bar, said plate being yieldable relative to the supporting bar to receive a portion of a closure unit therebetween, and said springs exerting yielding tension on said 5 plate to hold said unit in place.

Des Moines, Iowa, February 12, 1930.
